UNITED STATES PATENT OFFICE

90,402

DESIGN FOR A CHANGEABLE SHEET BULLETIN BOARD

John B. D'Ippolito, Vineland, N. J., assignor of one-half to Arthur L. Joseph, Vineland, N. J.

Application May 18, 1933. Serial No. 48,158

Term of patent 3½ years

To all whom it may concern:

Be it known that I, JOHN B. D'IPPOLITO, a citizen of the United States, residing at Vineland, in the county of Cumberland and State of New Jersey, have invented a new, original, and ornamental Design for a Changeable Sheet Bulletin Board, of which the following is a specification, reference being had to the accompanying drawing, forming part thereof.

I claim:

The ornamental design for a changeable sheet bulletin board as shown.

JOHN B. D'IPPOLITO.
